ATTORNEY

UNITED STATES PATENT OFFICE

2,269,031

TANK BLEEDER VALVE

William J. MacArthur, Los Angeles, Calif.

Application July 1, 1939, Serial No. 282,443

2 Claims. (Cl. 210—169)

The object of the invention is to provide an apparatus for automatically draining the layer of free water which accumulates in tanks holding crude petroleum, petroleum distillates, and the like.

The invention is best described with reference to the attached drawing, in which

Fig. 1 is an elevation of an illustrative embodiment of the invention, parts being broken away to show details of internal construction;

Fig. 2 is a fragmentary section in plan, as on the line 2—2 of Fig. 1, and

Fig. 3 is a section, as on the line 3—3 of Fig. 2, of a modified form of the mating grids 27 and 31.

Referring to the drawing: 10 is a hollow body or case, as of cast iron, provided with a cover plate 11 retained by a plurality of clamp bolts 12. The case has on its lower side a threaded collar 13 to receive an inlet pipe, and may also be provided with a removable clean-out plate 14 covering an opening not shown in the lower side of the case. The cover plate is provided with an outlet tube 15 which is shown as broken off and may be threaded or flanged for pipe connection.

Centrally the cover plate is provided with a stuffing box 16, a gland 17, and a follower 18 which is urged by a spring 19 to compress flexible packing 20.

The functioning portion of the device consists of two mating circular grids, one of which is movable in relation to the other. Describing first the movable grid element: a stem 21 passes through the stuffing box and is connected at its upper end with a pivoted link 22 and hand lever 23 to be raised and lowered manually through a short distance. At its lower end the stem is provided with a flange 24, a plurality of deep radial ribs 25 forming a spider, a rim ring 26 slidingly fitting within the case, and a plurality of upwardly projecting, circular and concentric ribs 27 supported by said spider.

The stationary grid element has a central hub 28 bored to fit stem 21, a flange 29 resting on the upper edge of the case, a plurality of deep radial ribs 30, and a plurality of downwardly projecting, circular and concentric ribs 31.

These grids, as shown, are so formed that the adjacent ribs 27 and 31 leave narrow annular channels 32 for the passage of water. The direction of flow through the device is indicated by arrows in Fig. 1; through the inlet connection 33 into the space 34 below the pair of grids, then in parallel through all of the channels 32 between the ribs 27 and 31 constituting the grids, and

thence through space 35 above the grids into outlet connection 15.

Two alternative types of concentric ribs are shown. In the form shown at the right side of the Fig. 1 the ribs 27 and 31 are rectangular in section and the spaces between them are predetermined in the machining of the two elements and are of constant width regardless of the relative positions of the two grids, to the point where the ribs of the lower element are wholly withdrawn from the spaces between the ribs of the upper element. In the form shown in Fig. 3 the circular ribs are oppositely beveled and the spacing between the opposed ribs may be varied by raising and lowering the stem and with it the lower grid assembly.

The functioning of this device depends on the fact that the surface tensions of hydrocarbon oils materially exceed that of water, and a very narrow annular channel may be so adjusted in width as to permit water to flow freely and to shut off the flow as soon as oil tries to enter the channel. In my experience the most suitable spacing between the two grids ranges from $\frac{1}{1000}$ inch for gasoline to about $\frac{15}{1000}$ inch for heavy crude oils. The most accurate machining of the two grids to ensure concentricity and even spacing is essential.

With the apparatus coupled to the drain pipe of an oil tank in the upright position shown, water will flow through the channels between the grids until the water layer in the tank is completely withdrawn and oil enters the case. As this oil lies below the grids and cannot pass through, no fluid will pass even when water has again collected in the tank, until the oil is flushed out. For this purpose the hand lever 23 is depressed until the spacing between the two grids is sufficiently wide to allow the oil to pass through and be followed by water. In this position the valve acts as an automatic stop, but manual flushing is required to reestablish drainage. If placed in the inverted position, water collecting in the tank after draining will gradually displace the oil from the case and, in the absence of thick emulsion, will again start to flow through the valve after an interval of cessation. It is highly desirable to provide a strainer in the inlet pipe to the device to stop sediment and prevent too rapid fouling of the apparatus.

While the above description refers only to a circular form, it will be evident that the ribs of the two grids could be straight and parallel and the case be rectangular without in any manner changing the results produced by the device.

I claim as my invention:

1. An automatic tank bleeding valve comprising: a case with inlet and outlet openings; a pair of grids arranged across said case between said openings, said grids having spaced parallel ribs, the ribs of each grid being arranged to enter the spaces between the ribs of the opposite grid to leave narrow channels for the passage of liquid laterally through said grids, the walls defining each said channel being substantially parallel, and means for manually advancing and retracting one of said grids as regards the other of said grids.

2. An automatic tank bleeding valve comprising: a case with inlet and outlet openings; a fixed grid arranged across said case between said openings and a movable grid mating with said fixed grid to leave a plurality of narrow channels for the passage of liquid laterally through said grids, the walls defining each said channel being substantially parallel, and means for adjusting the spacing between said grids to controllably vary the width of said channels.

WILLIAM J. MACARTHUR.
